United States Patent Office

Des. 205,898
Patented Oct. 4, 1966

205,898

GAME BOARD

Christian F. Murer, 750 W. 48th Ave., Denver, Colo.

Filed May 14, 1965, Ser. No. 85,290

Term of patent 7 years

(Cl. D34—5)

The figure is a plan view of a game board showing my new design. The edge is of conventional thickness.

I claim:

The ornamental design for a game board, as shown and described.
